UNITED STATES PATENT OFFICE

117,281

DESIGN FOR A GOLF CLUB COVER

Joseph Henry Lamkin, Chicago, Ill., assignor to White-Lamkin, Inc., Chicago, Ill., a corporation of Illinois

Application April 24, 1939, Serial No. 84,535

Term of patent 7 years

To all whom it may concern:

Be it known that I, Joseph Henry Lamkin, a citizen of the United States, residing at Chicago, in the county of Cook and State of Illinois, have invented a new, original, and ornamental Design for a Golf Club Cover, of which the following is a specification, reference being had to the accompanying drawing forming part thereof.

Fig. 1 is a front view of a golf club cover showing my new design.

Fig. 2 is a rear view of the golf club cover illustrated in Fig. 1.

I claim:

The ornamental design for a golf club cover, as shown.

JOSEPH HENRY LAMKIN.
